No. 793,339.

PATENTED JUNE 27, 1905.

W. B. BASSELL.
EXTENSION CAR STEP.
APPLICATION FILED JUNE 27, 1904.

UNITED STATES PATENT OFFICE.

WILLIAM B. BASSELL, OF COLUMBUS, OHIO.

EXTENSION CAR-STEP.

SPECIFICATION forming part of Letters Patent No. 793,339, dated June 27, 1905.

Application filed June 27, 1904. Serial No. 214,255.

To all whom it may concern:

Be it known that I, WILLIAM B. BASSELL, a citizen of the United States, residing at Columbus, in the county of Franklin and State of Ohio, have invented a certain new and useful Improvement in Extension Car-Steps, of which the following is a specification.

My invention relates to a new and useful improvement in extension car-steps.

The object more particularly resides in the provision of pneumatic means which may be readily connected with the air-brake system of the car for operating the steps.

Another object lies in means for locking the treads in their extended position when the passenger steps thereon.

Finally, the object of the invention is to provide a device of the character described that will be strong, durable, and efficient, and simple and comparatively inexpensive to make, and one in which the several parts will not be liable to get out of working order.

With the above and other objects in view the invention consists of the novel details of construction and operation, a preferable embodiment of which is described in the specification and illustrated in the drawings, wherein—

Figure 1 is a transverse sectional view of a car-platform, showing my improved steps in elevation and in their raised position. Fig. 2 is a similar view showing the steps extended. Fig. 3 is a side elevation of the operating mechanism. Fig. 4 is a longitudinal vertical sectional view of the operating mechanism. Fig. 5 is a bottom plan view of the operating mechanism; and Fig. 6 is a rear elevation of one of the steps, showing the platform in section and the lowermost step extended.

In the drawings the numeral 1 designates the platform of the car, from each side of which project the fixed steps 2. Hangers 3, secured to the outer lower portions of the steps 2, pivotally support yokes 4, which latter pivotally support at their lower ends the extension steps or treads 5. Extending from the rear of the treads or steps 5 are upwardly curved arms 6, formed with elongated loops 7 and contracted ends 8, which are adapted to engage in the teeth 9 of the curved rack-bars

10, which latter are supported from the rear sides of the steps 2. The arms 6 are supported by bails 11, which pass through the elongated loops 7 and are pivotally mounted at their free ends upon the under side of the 55 steps 2.

The elongated loops 7 allow the arms 6 a limited play upon the bails, so that when the treads 5 are in their extended position, as shown in Fig. 2, pressure applied thereon 60 forces the arms 6 upward, causing the ends or points 8 to engage in the teeth 9 of the rack-bar 10, and thus prevent the steps from swinging backward. When the pressure is removed from the treads 5, the steps will swing 65 slightly outward and the arms 6 drop to their normal position.

For raising and lowering the steps I provide a pneumatic device, which comprises a fixed cylinder 12, having a thickened end wall 70 13, from which extend brackets 14, which are secured to the under face of the platform and by which the device is supported. An air-supply pipe 15, which may be connected with the air-brake cylinder, passes through the wall 75 13 for the purpose of delivering air into the cylinder. A suitable valve (not shown) may be arranged in the pipe 15 for controlling the air-supply.

A plunger-cylinder 16, having an enlarged 80 head 17, fits snugly within the cylinder 12, so that when air is forced into the cylinder 12 the plunger-cylinder 16 is driven outward, and when the air is exhausted the said cylinder is drawn inward by a spring 31, secured 85 at one end to cylinder-wall 13 by a bow 32 and at the other end to plunger-head 17 by eye 33. Extending rearwardly from the head 17 is an arm 18, which normally stands in the recess 19, formed in the lower end of the end 90 wall 13. A pin 20, secured in the end of the arm 18, projects downwardly through the elongated slot 21 of a longitudinally-extending plate 22, secured along the lower edge of the end wall 13. Pivoted upon the under 95 face of the plate 22 by means of the pivot-screw 23 is an irregular-shaped lever-plate 24, provided at its opposite ends with eyes 25, from which extend oppositely-disposed links 26, having a pivotal engagement at their outer 100

ends with the yokes 4. The plate 24 is formed near its inner end with a curved slot 27, having recessed ends 28 and 29.

The pin 20, which, as before described, 5 passes through the slot 21, also passes through the curved slot 27, and when the parts are in their normal position—that is, the steps being raised and the plate 24 being in the position shown in full lines in Fig. 5—the pin 20 10 rests in the recess 29 of the slot 27, the plunger-cylinder being drawn in by the vacuum created by the exhaustion of the air therefrom. When the vacuum in the cylinders 12 and 16 is relieved and the air forced into the 15 same under pressure, the cylinder 16 will be driven outward, as indicated in dotted lines in Fig. 5. As the cylinder 16 moves outward the pin being carried by the arm 18 is guided in the slot 21, thus preventing the cylinder 20 from turning. During this outward movement the pin impinges the inner wall 30 of the slot 27, which owing to its curved formation travels along the side of the pin, thus forcing the lever-plate 24 to one side and the 25 pin finally resting in the recess 28, as shown in dotted lines in Fig. 5. This swinging movement of the plate 24 throws the links 26 outward, thus causing the treads or steps 5 to be swung downward, as shown in Fig. 2. 30 The pressure being relieved in the cylinders, the parts are returned to their normal position by spring 31. It will be readily seen that the steps may thus be conveniently controlled from the point at which the air-brake-controlling means is regulated—on railroads in the cab of the engine and on street-cars upon the platform in juxtaposition to the 35 brake-controlling apparatus.

It is apparent that the device is entirely au-

tomatic and that the raising and lowering of the steps or treads 5 may be readily and expeditiously accomplished.

I do not wish to limit myself to the exact details of construction herein set forth, as I may make various changes in the same without departing from the spirit of my invention.

Having now fully described my invention, what I claim, and desire to secure by Letters Patent, is—

1. The combination with an adjustable tread, of pneumatic means for operating the tread, and automatic means for locking the tread in operative position.

2. The combination with an adjustable 5 tread, of a swinging plate having a cam-slot and connected to the tread for adjusting the same, and mechanism having a movable part 10 engaging in the cam-slot for swinging the plate.

3. The combination with an adjustable tread, of pneumatic means for adjusting the tread comprising a fixed cylinder, a movable cylinder slidably mounted on the fixed cylinder, a swinging plate operatively connected 6 to the movable cylinder, and means for connecting the plate with the tread.

4. In a device of the type set forth, the combination with a fixed cylinder, and a movable cylinder carrying a projection, of a 7c swinging plate having a slot therein in which the projection travels whereby the plate is swung when the last-named cylinder is moved.

WILLIAM B. BASSELL.

In presence of—

A. L. PHELPS,
W. L. MORROW.
